UNITED STATES PATENT OFFICE

2,442,090

STRAIGHT BAR KNITTING MACHINE

John Edward Lynam, Mapperley, and Patrick Gideon McCarthy, Whitwick, England, assignors to William Cotton Limited, Loughborough, Leicestershire, England

Application April 25, 1946, Serial No. 664,924
In Great Britain March 20, 1945

10 Claims. (Cl. 66—126)

1

This invention concerns Cotton's Patent and other straight bar knitting machines and one of its objects is the provision of a mechanism for such machines whereby a given displacement of one member may be variably transformed into displacement of a driven member and in particular mechanism whereby the traverse of a carrier, driven positively from a member of the drawn mechanism that reciprocates with a constant amplitude, may be varied as required without the use of a friction box or other slipping clutch.

The invention provides, in or for a Cotton's Patent or other straight bar knitting machine, mechanism for converting a given displacement in one direction into a variable displacement in another direction, comprising a converter consisting of track members conjointly defining a track having two offset and preferably parallel ends and an oblique or inclined middle part joining them, which track members are relatively adjustable to vary the offset between the two end parts, and a follower for engaging said track, whereby relative movement between said follower and converter causing the follower to pass from one end part to the other produces a relative displacement in a transverse direction the amplitude of which is determined by said adjustment. The converter may be driven to and fro, the follower being restrained against movement with the converter, but other forms of relative movement between the converter and the follower are within the scope of the invention. In applying this mechanism to a carrier drive the converter will therefore be driven (preferably with a constant amplitude) by the Coulier or draw mechanism and the follower will be connected to the carrier through a coupling that transmits the transverse displacement only.

These and other features of the invention set out in the appended claims are incorporated in the construction that will now be described as an example of the application of the invention to the draw mechanism of a Cotton's Patent or other straight bar knitting machine for driving a carrier with a variable amplitude of traverse, with reference to the accompanying drawings in which:

Figure 1 is a diagram illustrating the operation of the mechanism in a simple form;

Figure 2 is a rear elevation of the relevant portions of a straight bar knitting machine, illustrating a practical embodiment of the invention;

Figure 3 is a view looking in the direction of arrow A in Fig. 2;

2

Figure 4 is an end elevation of the mechanism shown in Fig. 2;

Figure 5 and Figure 6 show certain racking mechanism;

Figure 7 and Figure 8 show details of the mechanism shown in Fig. 5;

Figures 9 and 10 show alternative methods of driving the converter, while

Figure 11 is a sectional view illustrating a detail of the mechanism shown in Fig. 10.

Turning now to Fig. 1 the converter therein illustrated is reciprocated horizontally with a constant amplitude (by appropriate draw or Coulier mechanism) and consists of two track members 1, 2, defining upper and lower horizontal end tracks 3a, 3c, the member 1 having a downwardly inclined bottom track wall 1a and the member 2 an upwardly inclined track wall 2a parallel to it so that between these inclined walls 1a, 2a there is formed an inclined middle track 3b which communicates between the two track ends 3a, 3c. The two track members 1, 2 are adjustable lengthwise of the middle track 3b between a position in which the two end tracks 3a, 3c are aligned and positions in which the two end tracks are spaced apart to any required extent. A lozenge-shaped follower 4 is movable along the track. Therefore in the first mentioned position of adjustment the follower 4 passes straight from one end track to the other without vertical displacement but, in all other positions of adjustment of the track members 1, 2 it travels up or down the inclined centre track 3b in its movement from one end track to the other and is therefore displaced vertically to an extent depending upon the adjustment of the track members 1, 2. This vertical displacement is applied to driving a carrier horizontally, and therefore the converter provides a means whereby the traverse of a carrier may be varied, as required, from nothing upwards.

Any suitable coupling may be interposed between the follower 4 and the carrier so that only the vertical displacement is communicated to the latter as horizontal movement. For example the follower 4 may be connected to a vertical rack 5 gearing with a pinion 6 which gears with a rack on a carrier driving bar 7. If the follower 4 is driven to and fro with constant amplitude by appropriate draw mechanism, and the converter is stationary, then the pinion 6 will travel horizontally with the vertical rack 5 and is slidably keyed or splined to a horizontal shaft which is connected to a carrier driving bar 7 by bevel gearing, a pinion, and a rack on said bar. The

carrier may be driven from the driving bar 7 by a bolt 8 received in a slot (in a driving lug 9).

The track members 1, 2 are preferably adjusted in conformity with the adjustment of carrier stops, for example by screw mechanism or lead screws 10, 11 that is racked as the carrier stop screws are racked. In the case of a main carrier, both track members 1, 2 are racked with the selvedge stops, but in the case of a converter driving a plating carrier that traverses only part way with the main carrier (as for one high heel part) one track member is racked with a selvedge stop and the other with a graduating stop.

The application of the invention to driving a pair of splicing carriers such as those employed for the high heel splicings, and for splicing the marginal parts of a French foot, in the production of a fully fashioned stocking blank is illustrated in Figs. 2 to 11. It will be appreciated that while each of these carriers must travel in advance of the slur cock and in the required relation to the main carrier that travels completely across the blank, one of them must complete its travel before the other starts in each draw. Therefore each carrier has its own converter of the general construction shown in Fig. 1. In Fig. 2, the track members of these two converters are therefore numbered 1, 2 and 1¹, 2¹, and the followers are numbered 4 and 4¹. The mechanism is preferably situated at the rear of the machine where it can conveniently be mounted on the frame member 12 as shown in Fig. 2. A fixed dovetailed bar 13 is carried by brackets 14, 14¹ fastened to frame member 12 and on this runs a corresponding slipper 15 carrying the adjustable track members 1, 2 and 1¹, 2¹ of the two converters. These track members are screwed on to auxiliary dovetail bars 17, 18 and 17¹, 18¹, which operate in corresponding inclined sideways cut into the face of the slipper 15. The movement of track members 1, 2, 1¹, 2¹ is effected by means of lead screws 10, 11 and 10¹, 11¹, these being supported at their outer ends, and also prevented from moving laterally, by end plates 19. Each screw carries at its outer end, a skew gear 20, 21, 20¹, or 21¹ and a dividing plate 22. Meshing with these skew gears are further skew gears, 23, 24, 23¹, 24¹ slidably mounted on splined shafts 25, 26 and 25¹ and held in register with the first-mentioned gears by brackets 27 and 28. The splined shafts are supported at their outer ends by stationary auxiliary brackets 29 and 29¹, and at their inner ends by lugs provided on brackets 14, 14¹. The operating means for these shafts will be dealt with in detail later.

It will be appreciated that the two track members 2 and 2¹ are adjusted simultaneously by shaft 26, while the two cams 1 and 1¹ are adjustable independently of one another and of track members 2, 2¹, by means of shafts 25, 25¹. Furthermore, since the gears 23, 23¹, 24, 24¹ are slideable along the shafts, this adjustment may be carried out irrespective of the reciprocation of the slipper 15.

Mounted at the rear of the foregoing mechanism are two vertical sliding bars 5 and 5¹, which operate in suitable bearings formed in brackets 14, 14¹. These bars 5, 5¹ carry the respective followers 4, 4¹ which slide in the tracks formed by track members 1, 2 and 1¹, 2¹. Referring particularly to Fig. 2 and assuming that the slipper 15 is travelling from left to right, it will be seen that follower 4 is travelling up the incline between track members 1 and 2 and therefore, imparting an upward vertical motion to the bar 5 while

follower 4¹ is between the horizontal faces of track members 1¹ and 2¹ so that bar 5¹ is stationary. As the slipper advances however, conditions will be reversed and bar 5 will reach its highest position and then remain stationary while bar 5¹ will commence to travel in a downward direction. Finally, as the slipper 15 reaches the right hand end of its movement both bars 5, 5¹ will become stationary.

10 It will now be appreciated that by suitably adjusting the track members 1, 2, 1¹, 2¹ the length of the movement of bars 5, 5¹ can be varied as required from a point at which no movement takes place at all to a maximum determined by 15 the size of the mechanism. It should also be noted that the upper and lower limits of travel of the bars 5, 5¹ are independent and also that the upper limits of the two bars are independent of each other. The lower limits of the two bars are always the same. These matters being appreciated, it will be seen that the apparatus disclosed is well adapted to drive two splicing carriers in a fully fashioned hose frame, one carrier finishing its traverse in each draw before the other carrier starts. In such a machine, the simultaneous adjustment of both track members 1 and 1¹ governs the outer limits of travel of the two carriers (such limits being coincident with the selvedges of the fabric) and the adjustment of track members 2, 2¹ governs the inner limits of travel of the two carriers.

In order to connect the variably driven bars 5, 5¹ to their respective carriers, chains 30, 30¹ are fixed to their upper and lower ends, the chains 35 themselves running round sprockets 31, 32 and 31¹, 32¹. The upper sprockets 32, 32¹ are fixed on the outer ends of two horizontal shafts 33 and 33¹ carried by brackets 14, 14¹ at their outer ends and by brackets 34, 35 at their opposite ends. 40 The inner ends of shafts 33, 33¹ respectively carry pinions 36, 36¹ meshing each with one of two slidably mounted racks 37, 37¹. These racks carry brackets 38, 38¹ which in turn support pivoted carrier driving fingers 39, 39¹ for connecting with the carrier rods 40, 40¹ by means of lugs 41, 41¹. Thus the variable stroke imparted to bars 5, 5¹ is converted to a rotary motion in shafts 33, 33¹ and then to the horizontally reciprocating motion of varying amplitude of the carrier rods 40, 40¹.

50 When the splicing or plating is commenced, just above the heel of the stocking, it is necessary for one of the carriers to come into operation one course prior to the other and to effect this, each of the carrier driving fingers 39, 39¹ is pivoted 55 so that it can be swung upwards out of action by means of a stud 42 on automatic control shaft 43.

Figs. 2, 9 and 10 show three alternative modes 60 of driving the main slipper 15, a feature of the movement of the slipper being that it must operate slightly in advance of the slur cock in order to give the necessary "plating lead" to the carriers. Preferably this is arranged by means of a separate draw mechanism, comprising the known draw cam 44, reciprocating draw bar 45, draw lever 46 pivoted on bracket 47 and connected to the draw bar by means of a cross head at 48. In order that the plating mechanism (i. e. slipper 15 and associated parts) shall not be continually 65 in operation while making the welt and leg of the stocking when it is not required, the connection between draw lever 46 and slipper 15 takes the form of a detachable link 49 which can be lifted 70 out of engagement with driving pin 50 as and

when required by means of studs 51 on the aforementioned automatic control shaft 43.

The timing of this draw cam 44 would be slightly in advance of the slur cock draw cam but not so far advanced as the normal carrier draw cam.

The alternative mode of driving shown in Fig. 9 is taken from the existing carrier draw cam and draw lever 52. This is already timed in advance of the slur cock draw by the amount necessary to provide the normal carrier lead and this must be cut down by about half to give the correct plating lead. This can most readily be accomplished by widening the slotted end of link 49 as shown at 49a. Thus at each reversal of the draw mechanism the pin 50 moves from one end of slot 49a to the other, thereby allowing the plating carriers to lag behind the main carriers.

A further possible mode of controlling the slider 15 is shown in Figs. 10 and 11 where the drive is taken from the slur cock draw (not shown) by means of a connecting bar 53. Were this bar 53 connected directly to link 49 it is obvious that the plating carriers would run above the slur cock instead of in advance of it and therefore, the following mechanism is interposed between bar 53 and link 49. The driving bar 53 carries a bracket 54 which in turn supports a shaft 55 on which a pinion 56, and an eccentric 57 coupled to it, are journaled. The bracket 54 also supports a short horizontal rack 58 meshing with pinion 56, the rack being held in such a position that it can cooperate with the fixed stops 59 and 60 at either end of the travel of connecting bar 53. The link 49 is mounted on eccentric 57 and thus at each end of the draw the rack 58 engages stop 59 or 60 and is shogged in the bracket 54; in so doing it rotates pinion 56 and eccentric 57, thereby advancing link 49 in relation to connecting bar 53.

It now remains to describe the mechanism for racking the lead screws 10, 11, 10¹, 11¹; this mechanism is shown in Figs. 5, 6, 7 and 8.

Track members 1 and 11 are controlled by lead screws 10 and 10¹ and are operated in conjunction with the graduated splicing stop screws already existing on the machine. These latter are racked independently and in either direction under controlling influence of a pattern chain 61. Since the screws 10 and 10¹ must follow the graduated splicing stop screws it becomes necessary to adapt the same pattern chain 61 to the control of these screws as shown in Figs. 5, 7 and 8.

Since the mechanism for racking the two lead screws 10, 10¹ is identical, only that for racking one screw 10 through the medium of its splined shaft 25 is shown in Fig. 5. Certain portions of the mechanism for the other lead screw 25¹ are shown in Figs. 2 and 5 and are given primed reference numbers. The racking is carried out by lever 62 carrying pawls 63 and 64, for forward and back racking respectively, operating on rack wheels 65 and 6. The lever 62 is operated by cam 67 on main cam shaft 68 by means of a shogging truck 69 controlled by fork, 70, rod 71, bell crank lever 72, link 73, and a further bell crank 74. The two pawls 63, 64 are controlled by a bluff plate 75 which determines whether the pawls should both be held out of action (i. e. a neutral position) or whether one or the other shall rack. Bluff 75 is operated from the pattern chain 61 by means of a stud lever 76, bell crank lever 77 and link 78. Thus if a low stud is fastened to chain 61, the bluff 75 takes up a neutral position, if the

stud is removed the pawl 63 will drop into action while a high stud will allow pawl 64 to operate.

The truck 69 is shogged into register with cam 61, each time a selecting stud operates stud lever 65 or 76¹, by means of bell crank lever 74 which extends across both stud levers.

In Fig. 5 the commencement of the corresponding mechanism for lead screw 10¹ is shown at 76¹, 77¹, 78¹, while in Fig. 2 are shown the terminal portions of said corresponding mechanism consisting of rack wheels 65¹, 66¹ on shaft 25¹, pawls 63¹, 64¹, bluff 75¹, and pawl-operating lever 62¹.

The lead screws 11 and 11¹ are operated in conjunction with the selvedge stop screw and do not have to operate independently of each other; therefore, only one racking mechanism is required. This is shown in detail in Fig. 6. Racking arm 79 is operated by cam 80 on main cam shaft 68 by means of shogging truck 81 and fork 82 on control rod 83. This control rod 83 is the existing rod which normally operates the shogging truck on the selvedge stop screw rack lever. The lever 79 carries at its outer end pawls 84 and 85 operating on rack wheels 86 and 87 and controlled by bluff plate 88. Bluff 88 is in turn operated by studs 89 on the automatic control shaft 43. The splined shaft 26 which controls lead screws 11 and 11¹ is also provided with a hand racking device consisting of mitre wheels 90, 91, shaft 92 and handle 93, Fig. 2. This is used for re-setting the screws at the end of each cycle of operations. A similar device is not necessary for lead screws 10 and 10¹ as these are automatically returned to their starting positions by suitably setting out pattern chain 61.

We claim:

1. For a Cotton's Patent or other straight bar knitting machine, mechanism for converting a given linear displacement in one direction into a variable linear displacement in another direction, comprising a converter consisting of track members conjointly defining a track having two offset end parts and an oblique or inclined middle part joining them, which track members are relatively adjustable to vary the offset between the two end parts, and a follower for engaging said track, whereby relative movement between said follower and converter causing the follower to pass from one end part to the other produces a relative displacement in a transverse direction the amplitude of which is determined by said adjustment.
2. Mechanism according to claim 1, being carrier driving mechanism.
3. Mechanism according to claim 1, having the converter reciprocatable.
4. Mechanism according to claim 1, having a driven member movable to and fro, and rack and pinion mechanism for driving it from the follower.
5. In a straight bar knitting machine having two carriers, mechanism for driving them independently comprising for each carrier a converter consisting of track members conjointly defining a track having two offset end parts and an oblique or inclined middle part joining them, which track members are relatively adjustable to vary the offset between the two end parts, and a follower for engaging said track, whereby relative movement between said follower and converter causing the follower to pass from one end part to the other produces a relative displacement in a transverse direction the amplitude of which is determined by said adjustment, and means for

connecting the followers to the respective carriers.

6. A machine according to claim 5, having means for reciprocating the pair of converters in unison.

7. A machine according to claim 5, having the two converters so disposed that the two followers operate one after the other.

8. A machine according to claim 5, having means for reciprocating the pair of converters in unison, and having the two converters so disposed that, at the end of relative movement in either direction, one follower is in one offset part of its track and the other follower is in the opposite offset part of its respective track, and having the two tracks oppositely arranged.

9. In a straight bar knitting machine having two carriers, mechanism for driving them independently comprising for each carrier a converter consisting of track members conjointly defining a track having two offset end parts and an oblique or inclined middle part joining them, which track members are relatively adjustable to vary the offset between the two end parts, and a follower for engaging said track, whereby relative movement between said follower and converter causing the follower to pass from one end part to the other produces a relative displacement in a transverse direction the amplitude of which is determined by said adjustment, means for connecting the followers to the respective carriers, means mounting said converters with the two tracks oppositely disposed, means for re-

ciprocating the two converters in unison with a relative disposition such that, at the end of relative movement in either direction, one follower is in one offset part of its track and the other follower is in the opposite offset part of its respective track, and means for adjusting like track members of the two converters in unison.

10. In a straight bar knitting machine having a reciprocatable slur cock, carrier driving mechanism comprising a converter consisting of opposed track members defining between them two offset and parallel track ends and an inclined middle part joining them, adjusting means for adjusting at least one track member lengthwise of said inclined part to vary the length thereof and to vary the offset between the two ends, a follower engaging in said track and movable thereby, upon relative reciprocation between converter and follower lengthwise of said ends, in a transverse direction, means for coupling the follower to a carrier to drive the latter to and fro with a variable amplitude of traverse, and means for effecting said reciprocation with a lead over the slur cock.
